INTERNAL SIPHON GAUGE

Maximilian Klein, Sellersville, Pa., assignor to
United States Gauge Company, New York,
N. Y., a corporation of Pennsylvania

Application December 3, 1936, Serial No. 114,050

9 Claims. (Cl. 73—109)

This invention relates to pressure gauges of the type wherein it is necessary or desirable to provide some means for preventing the entry of the fluid, the pressure of which is being measured, into the pressure responsive element.

Such means is usually in the form of a trap or so-called "siphon" and commonly consists of a looped tube connecting the gauge with the source of fluid pressure. If such looped tube or "pigtail" is located externally of the gauge it is exposed to damaging blows and is also unsightly in appearance. It has been proposed to locate the trap or siphon within the confines of the gauge casing where it is protected and out of sight. Internal traps or siphons of this general type have not been wholly satisfactory, especially from a manufacturing standpoint as they involve complicated tubing arrangements and either radical modifications of existing gauge structures or an excessive number of soldering operations, which result in increased production costs. The present invention is hence concerned with internal siphons or traps designed to obviate these difficulties.

A principal object of this invention is to provide a novel and improved internal siphon or trap which is simple and inexpensive to construct, efficient in operation and substantially universally adaptable to various existing types of pressure gauges without material alteration of the structure thereof.

Another object of this invention is to provide an improved internal siphon or trap which is of sufficient volume to provide a body of liquid large enough to entirely fill the pressure responsive device but which occupies but little added space within the gauge casing.

A further object of this invention is to provide an improved internal siphon or trap which is formed of a section of ordinary tubing secured at one end to the usual socket or post member and joined at its other end directly to the pressure responsive device or Bourdon spring.

A still further object of this invention is to provide novel means for supporting the joined ends of the siphon or trap tube and spring element on the post or socket member whereby both the siphon tube and the spring element are rigidly secured to the post or socket member.

Another object of this invention is to provide novel means for joining the ends of the siphon or trap tubing to the pressure responsive element or Bourdon spring element.

The above and other objects will become apparent from a study of the following detailed de-

scription of several preferred embodiments of my invention taken in conjunction with the accompanying drawings, wherein:

Figure 1 is a rear view of a pressure gauge embodying one form of my invention with the back 5 of the gauge casing cut away to show the interior thereof.

Figure 2 is a side elevation, partially in section, of the device shown in Figure 1 viewed from the left.

Figure 3 is a section of Figure 1 taken on line 3—3.

Figure 4 is a view similar to Figure 1 of another form of my invention, with the casing and movement mechanism omitted.

Figure 5 is a detail view showing a modified form of the joint between the Bourdon spring element and the section of tubing.

Figure 6 is a detail fragmentary view showing a modification of the device of Figure 4.

Figure 7 is a section of Figure 6, taken on the line 7—7 and showing the completed joint between the tubing and Bourdon spring.

Figure 8 is a view similar to Figure 7, but showing an intermediate step in the forming of the joint.

Figure 9 is a front elevation of another modification of my invention, the casing and internal gauge movement being omitted.

Figure 10 is a sectional view of the post or socket member of the gauge shown in Figure 9, taken on line 10—10, and showing the manner of securing the trap or siphon tube to the post or socket member.

Figure 11 is a front elevation of a further modification, with the gauge casing removed.

Figure 12 is a front elevation of another modification with the gauge casing omitted.

Figure 13 is a section of the post or socket member of Figure 12 taken on the line 13—13 of Figure 12 with the movement mechanism omitted, showing the manner of securing the siphon tube to the post or socket member.

Figure 14 is a front elevation of a still further modification with the gauge casing and movement mechanism omitted; and

Figure 15 is a section on line 15—15 of Figure 14, showing the post or socket member and the manner of securing the pressure responsive element thereto.

With continued reference to the drawings wherein like numerals are employed to designate like parts, and with particular reference to Figures 1 and 2:

The usual post or socket member 10 is pro-

vided with a threaded lower end 12 for connection to the source of fluid pressure and also with two rearwardly extending projections or bosses 14, 14, which serve as a supporting means for the casing 16, secured thereto by the screws 18, 18, and provided with the usual glass plate 19 held in place by the clamping ring 20. Mounted on the upper portion of member 10 is a frame plate 22 which is secured thereto by rivets 24, 24, 10 or other equivalent means, and carried thereby is a second parallel frame plate member 26 which is spaced therefrom by spacing posts 28, 28. A conventional movement mechanism is carried by the spaced plates 22, 26 and includes the 15 geared quadrant 30, the pointer shaft 32 and hairspring 34. This movement mechanism is conventional, forming no part of the present invention, and may take any other desired form. A dial 36 is mounted on the front face of the 20 socket member 10 in any suitable manner and the shaft 32 extends therethrough carrying the pointer 38.

A pressure responsive device or Bourdon spring element 44 is connected to the movement mechanism by a link 40 carried by an apertured element 42 mounted in the free end of said spring element, the other end of said element being joined to a section of ordinary round tubing 46 at 52 in a manner to be further explained. The 25 spring element is generally circular in shape and the tubing is curved similarly so as to surround the same as can be readily seen in Figure 1.

At one end the tubing 46 is secured to the post member 10 in a recess 47 by solder or any 30 other suitable means and communicates with the exterior of the post or socket member through suitable ducts or passages 49, 51. Adjacent to its other end the said tubing is secured to the back of the post member at 48 by solder or 35 equivalent means. Preferably, the lower boss member 14 is notched, as at 50, Figure 2, to receive the tubing and aid, with further solder if desired, in holding it in place.

Figure 3 shows a suitable manner of joining the Bourdon spring element 44 to the tubing 46. Said element is of lenticular cross-section and considerably thinner than the external diameter of the round tubing 46. The end of tubing 46 is fitted into the spring element by slightly bulging the same, as shown, and secured therein by soldering. While the solder is still hot the end of the spring element is squeezed together adjacent the tubing so as to close the end and bind it securely around the end of the tubing 44. This 45 forms a very tight and secure joint which is, at the same time, simple to make. As can be seen the Bourdon spring element 44 is entirely supported by a straight end portion of the section of tubing 46 and forms therewith a liquid trap 50 in a manner which will be further explained hereinafter.

In Figure 4 a modified form of the device shown in Figures 1 and 2 is illustrated. In this modification the back of post member 10 is provided with a groove or slot 62 which is of a depth approximately equal to the external diameter of the tubing 46. One end of said tubing is secured within the recess 47, as in Figure 1, while the other end thereof, adjacent to the joint 65 between the same and the spring element 44, is received in this slot 62 and secured therein by solder or by equivalent means which may take the form of a clamp member secured to said socket member over the slot 62. The lower boss 70 member 14 (not shown) if utilized in addition

to the upper boss 14 is fitted into its receiving aperture 63 after the tubing has been placed in the groove 62. In this form of my invention a relatively narrow spring element may be used and positioned so as not to project beyond the rear of post 10. It is thus possible to omit both of the boss members 14, 14 and secure the casing 16 directly to the back face of post 10, thus materially decreasing the thickness of the gauge.

In the foregoing modifications the joint 80 10 between the end of tubing 46 and the spring element 44 may be similar to that shown in Figure 3, except that the bulged portion of the spring element will be located approximately midway between the sides of the spring element, 15 due to the relative positions of the adjacent ends of the spring element and tubing, and the spring element will be squeezed together on both sides of the tube end. It is also possible to join the adjacent ends of the tubing and spring element 20 in the manner shown in Figure 5 by means of an adapter element 64. This adapter element is shaped so as to receive the round tubing 46 at one end and the flat spring element 44 at the other and these are secured therein by soldering 25 or other equivalent means.

In Figure 6 another manner of securing the end of the tubing to the post is shown which differs from that of Figure 4 in that the tubing 46 is flattened where it is to be received in the groove 62 and said groove is made correspondingly narrower. The flattened end 65 of the tubing 46 is joined to the Bourdon spring element as shown in Figures 7 and 8. The end of the spring element is spread open slightly to receive 35 the end of the tubing (see Figure 8) which is then soldered therein. While the solder is still hot the sides of the spring element are squeezed together slightly, as shown in Figure 7, thus clamping the spring element and tube end together and closing the end of the spring element with solder 66.

In the modification shown in Figures 9 and 10, the post or socket members 100 is provided with a rearwardly extending portion 112, threaded as at 114, and with forwardly projecting portions 116, 116 having tapped holes 117, 117. The usual gauge casing, not shown, is secured to the rear face 119 of the post or socket member 100, at 128, 128, and the dial (not shown) 45 is mounted on the portions 116, 116 by suitable screws engaging the tapped holes 117, 117. A conventional movement mechanism (not shown, but see Fig. 11) is secured to a face 118 of the socket member by suitable securing means 50 engaging the holes 120, 122. A projecting portion 124 is machined, or otherwise formed, on the post or socket member 100 to provide a ledge or shoulder 126, as shown in Figure 10. Instead of a ledge or shoulder 126 the portion 124 55 may be provided with a forwardly opening groove or slot similar to slot 127 in Figure 14.

A curved section of ordinary tubing 136 is secured at one end within a recess or hole 129 which communicates with the exterior of the 65 gauge through suitable ducts 130, 132, 134. At its other end the section of tubing has a straight portion which is seated on the ledge or shoulder 126 and secured thereto by solder as at 138, Figure 10. This end of the tubing 136 projects 70 slightly beyond the ledge and is fitted into and joined at 140 to the Bourdon spring element 142 in any of the manners above described. An apertured element 144, carried by the spring element is connected to the movement mecha- 75

nism, not shown, by means of a link, not shown, as in Figure 11.

The modification shown in Figure 11 is the same as that of Figures 9 and 10 except that the discharge end of tube 136 is passed through a cylindrical hole 125 provided in the projecting portion 124a of the post member 100a. Solder may be used to rigidly anchor the tube in the hole. The movement mechanism is shown attached to the face 118 by rivets 121 and comprises plates 150, 152 held in spaced relation by the posts 154, 154, a geared quadrant 156, pointer spindle 160 and hairspring 162. The geared quadrant is connected to the spring element 142 by the link 158, pivotally secured to the apertured element 144.

Figures 12 and 13 show a further modification of tube mounting means in a slightly different gauge structure. The post 200 is provided with a rearwardly extending portion 212 threaded as at 214, and with forwardly projecting bosses 216, 216. A casing, not shown, is secured to the rear face 219 of the post member 200 by suitable screws 228 and a dial (not shown) is secured to forwardly projecting portions 216, 216 by means engaging the tapped holes 217, 217. Plates 250 and 252, spaced by the posts 254, 254, and mounted on the post or socket member 200 by screws 221, carry a conventional movement mechanism comprising geared quadrant 256, pointer shaft 260 and hairspring 262. The quadrant is operatively associated with the Bourdon spring element by link 258 and element 244.

One end of the curved section of tubing 236 is secured in the hole 229 in the lower portion of the post member 200 and communicates with the exterior of the gauge through passages 230, 232, 234. The other end of said tubing is fitted into a slot or groove 225 provided in the projecting portion 216 and secured therein by solder as at 238. This end of the tubing is joined at 240 to the Bourdon spring element in any of the above explained manners.

In Figures 14 and 15 is shown a still further modification which is similar to those shown in Figs. 9 to 11. The post member 100b is the same as that shown in said figures and further description thereof is deemed unnecessary. In this modification the Bourdon spring element 142 is supported directly on the post member 100b and is joined to one end of the section of tubing 136 adjacent to said point of support by the joint 140. The other end of said tubing is secured to the member 100b and communicates with the exterior of the gauge in the same manner as in Figures 9 and 10. The details of the Bourdon spring support are as follows. A projection 131 on the front of member 100b is provided with a slot or groove 127. The spring element is positioned in said slot or groove and secured therein by soldering as at 138, or by equivalent means.

The operation of all of my improved siphons or traps is the same and is briefly as follows:

Steam or other fluid is admitted to the section of ordinary tubing through the passages provided in the post member and flows therethrough to the Bourdon spring element, the spring element is distorted by the pressure of the fluid and this distortion is indicated on the dial by the pointer, through the medium of the movement mechanism, in the usual manner. However, it is noted that the section of tubing extends upwardly above the highest point of the spring element thence downwardly to its point of attachment thereto. As shown, the tubing is

curved around the spring element in concentricity therewith but this exact form is not essential, as any form of the tubing which has a trap portion of substantial volume adjacent the open end of the spring element will suffice. It forms a simple and compact arrangement occupying but little extra space in the casing and not interfering with the gauge mechanism.

The downwardly extending portion of the section of tubing, together with the Bourdon spring element, forms a trap or siphon as can readily be seen from the several figures of the drawings. When steam is the fluid entering the gauge it condenses while passing through the section of tubing and into the spring element, such condensation being enhanced by the relatively thin walled structure of the same. Eventually the Bourdon spring element will be entirely filled with liquid, with the exception of space occupied by air trapped therein, and likewise the downwardly extending portion of the tubing will be filled with liquid. As this body of liquid is greater than the volumetric capacity of the spring element by an amount equal to the capacity of said downwardly extending portion it is obvious that its presence will effectively prevent the entry of high temperature steam into the spring element. The shape of the tubing section obviously precludes the escape of this body of liquid when the fluid pressure is cut-off.

In all the modifications the sections of ordinary tubing as well as the Bourdon spring elements are rigidly secured to the post or socket members in a simple but effective manner. No extra length of the expensive spring element is required and no costly modifications of gauge structure is entailed. As can be seen from the several modifications illustrated, my improved siphon or trap is readily adaptable to various types of gauges and is so arranged as to not interfere with the usual spring elements or operating mechanisms.

In this connection it is to be especially noted that a single conventional frame and movement may be universally used on the several embodiments described above by virtue of the type of joint used and also that the post or socket member may be conventional and of minimum size.

It is also pointed out that in respect to most of the forms shown, although any method of assembly may be followed, it is preferable to assemble the Bourdon spring element and the siphon tube prior to securing the same on the post or socket member. The soldered joint between these elements is first made and then the free end of the siphon tube and the end of same adjacent the joint, or the end of the Bourdon tube adjacent the joint, are secured in their respective recesses on the post or socket member. This facilitates the formation of the soldered joint between the Bourdon spring element and siphon tube as the same may be done on a bench and with the point of juncture readily accessible. Also the siphon tube can be left straight while this soldered joint is being made and later bent to its final form.

Thus it is seen that I have provided an improved internal siphon or trap for pressure gauges which is simple and inexpensive to construct, readily adaptable to various types of existing gauges without costly modifications thereof or the provision of expensive extra parts, and which occupies little extra space within the gauge casing, but which at the same time provides absolute protection to the Bourdon spring element.

by virtue of its large capacity and which is in all respects efficient in operation and positive in protection.

My invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a gauge of the type described, a socket member, a Bourdon spring element of generally circular shape, a circular section of cylindrical tubing surrounding said element secured at one end to said member and adapted to be connected at said end to a source of fluid under pressure, means securing the other end of said tubing to said member, and means joining said spring element to said last named end of said tubing, said spring element and a portion of said tubing forming a liquid trap.

2. In a gauge of the type described, a socket member having a projecting portion, a generally circular Bourdon spring element, a circular section of cylindrical tubing surrounding said spring element and joined thereto at one end, the other end of said tubing section being secured to said socket member and connected to a source of fluid pressure, a portion of said joined spring element and tubing assembly adjacent the point of juncture thereof being secured to said projecting portion.

3. In a gauge of the type described, a socket member provided with a shouldered portion, a circular section of cylindrical tubing secured at one end to said shouldered portion, a generally circular Bourdon spring element joined to said end of said tubing adjacent said shouldered portion, said tubing surrounding said spring element and secured at its other end to said member, said last named end of said tubing being adapted to be connected to a source of fluid pressure.

4. In a gauge of the type described, a socket member provided with a recess, a circular section of cylindrical tubing secured at one end in said recess, a generally circular Bourdon spring ele-

ment joined to said end of said tubing, the other end of said tubing being secured to said member and adapted to be connected to a source of fluid pressure, said tubing surrounding said spring element to form therewith a liquid trap.

5. In a gauge of the type described, a socket member provided with a recess on the back thereof, a generally circular Bourdon spring element, a circular section of cylindrical tubing surrounding said spring element and joined thereto at one end, the other end of said tubing section being secured to said socket member and connected to a source of fluid pressure, a portion of said joined spring element and tubing assembly adjacent the point of juncture being secured within said recess.

6. In a gauge of the type described, a socket member provided with a forwardly projecting portion having a groove in its upper surface, a generally circular Bourdon spring element, a circular section of cylindrical tubing surrounding said spring element and joined thereto at one end, the other end of said tubing section being secured to said socket and connected to a source of fluid pressure, a portion of said joined spring element and tubing assembly adjacent the point of juncture being secured within said groove.

7. In a gauge of the type described, a socket member, a generally circular Bourdon spring element, a circular section of cylindrical tubing surrounding said spring element and joined thereto at one end, the other end of said tubing being secured to said socket member and connected to a source of fluid pressure, a portion of said joined spring element and tubing assembly adjacent the point of juncture being secured to the back of said socket member.

8. In a gauge of the type described, a socket member, a Bourdon spring element, a section of tubing mounted at one end on said socket member, means for joining the opposite end of said tubing and an end of said spring element comprising an adapter device, and means for mounting one of said joined ends on said socket member, said tubing extending above said spring element to form therewith a liquid trap.

9. The combination set forth in claim 1 wherein said tubing is flattened at one end and said spring element is joined to said flattened end.

MAXIMILIAN KLEIN.
